(57) **CLAIM**

The ornamental design for a flexible printed wiring board, as shown and described.

DESCRIPTION

FIG. 1 is a front view of a flexible printed wiring board showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is an enlarged top plan view of the portion taken along line 7-7 in FIG. 3;

FIG. 8 is a bottom plan view of FIG. 7;

FIG. 9 is a front view of FIG. 7;

FIG. 10 is a rear view of FIG. 7;

FIG. 11 is a right side view of FIG. 7;

FIG. 12 is a left side view of FIG. 7;

FIG. 13 is another perspective view of FIG. 7 shown in a used condition with a power generation device shown in broken lines; and,

FIG. 14 is another perspective view of FIG. 13 shown in a used condition with a Photovoltaic module, junction box and Fresnel lens shown in broken lines.

(Continued)

The even dashed broken lines shown in the drawings represent portions of the flexible printed wiring board that form no part of the claimed design.

The dashed-dot-dashed lines indicate a boundary between the claimed and unclaimed surface areas.
